UNITED STATES PATENT OFFICE.

THOMAS F. NEAGLE, OF LEXINGTON, KENTUCKY.

HOBBLE FOR DRIVING-HORSES.

SPECIFICATION forming part of Letters Patent No. 659,856, dated October 16, 1900.

Application filed July 21, 1900. Serial No. 24,389. (No model.)

To all whom it may concern:

Be it known that I, THOMAS F. NEAGLE, a citizen of the United States, residing at the city of Lexington, State of Kentucky, have invented 55 a certain new and useful Improvement in Hobbles for Driving-Horses, of which the following is a full, clear, and exact description, such as will enable others skilled in the art to which it appertains to make and use the same, reference being had to the accompanying 60 drawings, forming part of this specification, in which—

Figure 1 is a view of a horse, showing my improved hobble in position thereon; and Fig. 15 2 is a detail view of the hobble.

This invention relates to a new and useful improvement in hobbles for driving-horses, the object being to train the horse to take high steps and to develop those muscles in the 20 front limbs to enable the horse to take such steps after comparatively little exercise with the hobble.

With this object in view the invention consists in the construction, arrangement, and 25 combination of the several parts, all as will hereinafter be described and afterward pointed out in the claims.

In the drawings, A indicates ankle-bands, which are preferably padded and secured in 30 position upon the ankles of the front feet by suitable straps and buckles a.

B indicates straps, which are attached to the ankle-bands A by means of suitable buckles b, one of such straps being on each side of the 35 ankle-bands. These straps are connected at their upper ends with an elastic cord C, said elastic cord shown in Fig. 1 as connecting the inside and outside straps together, respectively.

40 D indicates a pulley-block provided with two pulleys, over which the elastic bands C pass. Pulley-block D is provided with the usual swivel-eye d, through which eye passes a strap E, said strap supporting the pulley-block upon some suitable part of the harness—such, for instance, as the girth-strap.

In operation the hobble is attached as shown in Fig. 1, and when the horse is driven the elastic bands pass over the pulleys, exerting 45 a pull upon the lifted leg, so that said lifted leg will yield in a natural way to such pressure

and be lifted higher than would perhaps be done otherwise. In so lifting the front legs the muscles are developed to such an extent that the motion induced by the hobble will 55 be practiced by the animal without apparent effort after the horse has exercised some little time with the hobble. In practice it is desirable to place the hobble in position for about fifteen minutes during the morning and even- 60 ing exercise.

By adjusting the straps B and the strap E the tension of the yielding or elastic cords can be regulated so that the device may be adapted to horses having different gaits or to horses 65 of different sizes.

I am aware that minor changes in the arrangement, construction, and combination of the several parts of my device can be made and substituted for those herein shown and 70 described without in the least departing from the nature and principle of my invention.

Having thus described my invention, what I claim, and desire to secure by Letters Patent, is—

1. In a device of the character described, the combination with the ankle-bands designed to be secured to the fore feet of a horse, of an elastic cord connected to said ankle-bands, and a device carried by some suitable 80 support located between and to the rear of the fore legs, through which device said elastic cord is free to pass to accommodate the movement of the front feet and exert a lifting tension upon the fore feet by being connected to 85 said ankle-bands; substantially as described.

2. In a device of the character described, the combination with the ankle-bands designed to be secured to the fore feet of a horse, of elastic cords connected to the inner and 90 outer sides of said bands, a girth-strap, and a pulley-block secured to said girth-strap and through which said bands freely pass; substantially as described.

3. In a device of the character described, 95 the combination with ankle-bands designed to be secured to the fore feet of a horse, of adjustable straps secured to the inner and outer edges of one of said bands, elastic cords connecting said straps to the ankle-band of the 100 other foot, a girth-strap, a pulley-block through which said elastic bands freely pass,

and an adjustable strap connected to the girth-strap for supporting said pulley-block; substantially as described.

4. In a device of the character described, the combination with padded ankle-bands designed to be secured to the fore feet of the horse, elastic straps connecting said bands together, means for adjusting the tension of said straps, the girth-strap carrying a device 5 through which said elastic straps pass, and

means for adjusting the position of said device relative to the girth-strap; substantially as described.

In testimony whereof I hereunto affix my signature, in the presence of two witnesses, 15 this 18th day of July, 1900.

THOMAS F. NEAGLE.
